(57) **CLAIM**

We claim the ornamental design for a charger for shaver, as shown and described.

DESCRIPTION

FIG. 1 is a top, front, right side perspective view of a charger for shaver, showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings depict portions of the charger for shaver that form no part of the claimed design.

1 Claim, 5 Drawing Sheets
